ELECTRICAL APPARATUS

Joseph F. Kovalsky, Turtle Creek, Pa., assignor to
Westinghouse Electric Corporation, East Pittsburgh, Pa., a corporation of Pennsylvania

Application October 30, 1942, Serial No. 463,979

2 Claims. (Cl. 200—104)

1

This invention relates to electrical apparatus and, particularly, to the circuit controlling devices of regulators of the rheostatic type.

In the known circuit controlling devices of the rheostatic type and particularly those including a large number of spring biased contact members for shunting successive sections of a resistor, an elongated armature member responsive to a change in an electric quantity is generally used to actuate the contact members. Usually the elongated armature member is pivotally mounted on thin leaf springs of one form or the other in order to provide a substantially floating pivot.

Where the spring pivot for the armature member is of the cross-spring type, that is, two thin leaf springs in the horizontal position and two thin leaf springs in the vertical position to form a frictionless pivot along the line of intersection of the cross springs, it is found that in certain applications, the springs bend or buckle and prevent proper operation of the regulator. This is particularly true in applications where the voltage swings to a high value or where the regulator is subjected to high impact shocks as in navy applications.

In order to prevent such bending or buckling, it is necessary to use heavier leaf springs of the order of .012 to .020 inch thick, as compared to the thinner springs having a thickness of .008 to .010 inch. With such heavier springs, it is found that the performance of the regulator is affected, the sensitivity is reduced, and that it is impossible to correct the unbalanced condition by adjustments in the existing component parts of the regulator.

It is an object of this invention to provide in a regulator a circuit controlling device capable of withstanding physical shock and having a high degree of sensitivity.

Another object of this invention is to provide in a regulator a circuit controlling device having substantially balanced forces for obtaining a high degree of sensitivity in the operation thereof.

Other objects of this invention will become apparent when taken in conjunction with the accompanying drawing, in which:

Figure 1 is a diagrammatic view illustrating circuits and apparatus embodying the teachings of this invention;

Fig. 2 is a front elevational view of a regulator embodying the teachings of this invention;

Fig. 3 is a graph, the curves of which illustrate certain of the forces applied during a movement of the circuit controlling device;

2

Fig. 4 is a graph, the curves of which also illustrate certain of the forces applied during movement of the circuit controlling device; and

Fig. 5 is a graph, the curves of which are representative of the sensitivity of the regulator.

Referring to Figure 1, a circuit controlling device constructed in accordance with this invention is illustrated as disposed for controlling the voltage of a generator 10. The generator 10 is provided with an armature winding 12 connected to supply current to circuit conductors 14 and 16 and a shunt field winding 18. The shunt field winding 18 is connected at one end to the armature winding 12, the other end being connected through an adjustable rheostat 20 and a regulator resistor 22 to the other terminal of the armature 12.

A rheostat controlling element including a plurality of elongated conducting leaf springs 24 arranged in a stack and so mounted at one end that their fixed ends are insulated from each other and connected by conductors 26 to different points along the resistor 22 is disposed for controlling the number of sections of the resistor which are connected in circuit with the field winding 18. The other ends of the leaf springs 24 carry co-operating contact members (not shown) and are free to move in one direction, being self-biased in the other direction towards the sloped stop 28 of insulating material which functions to separate the springs 24 and contact members carried thereby when seated thereagainst.

A driving member 30 of insulating material is carried by a movable arm 32 and is so disposed to actuate the springs 24 into progressive engagement to sequentially shunt the sections of resistor 22. As illustrated, the movable arm 32 is pivotally mounted by a plurality of cross springs 34 and 36, two of each being provided on the core structure 38 of an electromagnet 40, the armature 42 of which is carried at the lower end of the arm.

In assembling the movable arm 32, a bracket 44 is secured to the arm, spaced vertical surfaces being provided thereon for receiving the upper ends of the spaced vertical springs 36 and spaced horizontal surfaces are provided for receiving one of the ends of the spaced horizontal springs 34. A supporting bracket 46 is secured to the core structure 38, as illustrated in Figs. 1 and 2, a part of the bracket being cut away in Fig. 1 to illustrate the assembly of the component parts. The bracket 46 is also provided with spaced horizontal surfaces for receiving one end of the horizontal springs 34 and spaced vertical surfaces for

receiving the lower ends of the vertical springs 36. When the ends of the horizontal and vertical springs 34 and 36, respectively, are mounted and secured to the brackets 44 and 46, as described hereinbefore, the line of intersection of the planes of the springs constitutes a frictionless pivot for the arm 32.

The electromagnet 40 having the core member 38 identified hereinbefore is provided with an energizing winding 48, the armature member 42 carried by the movable arm 32 being disposed for movement in the air gap formed in the core member as the energization of the winding 48 changes. The armature 42 is preferably tapered as illustrated so that as the armature moves in the air gap of the core member 38 in response to an increase in the energization of the winding 48, the width of the armature from top to bottom within the air gap will increase to effect an increase in the magnetic pull on the armature.

In order to actuate the movable arm 32 to operate the springs 24 to circuit closing position under certain conditions, a main coil spring 52 is provided having one end secured to the arm 32 and the other end secured to an adjustable bolt 54. The adjustable bolt 54 is carried by a bracket 56 which is secured to the core member 38 as illustrated. The pull of the spring member 52, the force of the leaf springs 24, and the taper of the armature 42 are so adjusted that the sum of the forces of the springs 24 and 52 for any position of the armature 42 within the regulating limits of travel is substantially balanced by the magnetic pull within the same limits of travel so that the positioning of the armature and, consequently, the positioning of the driver member 30 are determined by the degree of energization of the winding 48.

However, since the cross springs 34 and 36 forming the pivot for the arm 32 are made of relatively heavy material in order to prevent bending or buckling of the springs, they exert a force which upsets the balance between the spring forces and magnetic pull required for sensitive operation of the apparatus. As mounted the cross springs 34 and 36 have a zero bias on the movable arm 32 for some intermediate point between the limits of movement of the arm for the regulating limits of travel, as illustrated by the curve 58 of Fig. 3, but dependent upon the point at which balance is to be maintained. The zero bias point is usually selected to be near the open circuit position of the leaf spring assembly. The curve 60 of Fig. 3 is representative of the force of the leaf springs 24 of the stack as the stack is operated from an open to a closed position for the contact member, whereas curve 62 is illustrative of the unbalanced condition resulting from the use of the heavy cross springs 34 and 36. It is evident that with the heavier cross-spring pivot that the slope of the composite forces of the springs represented by curve 62 is quite steep over the regulating limits of travel.

In order to offset the change in the balance of the forces where the heavier springs 34 and 36 are employed, an auxiliary elongated leaf spring 64 is secured at one of its ends to one side of the movable arm 32 at its lower end by any suitable means, such as the bolt 66 and nuts 68. A projecting lug 70 is also provided at the lower end of the arm 32, the bolt 66 projecting through the lug 70, the arm 32, and the spring 64 to maintain them integral. As illustrated, the lug 70 and spring 64 are provided with a slot 72 and 74, respectively, to fit over the bolt 76 which is ad-

justably mounted on a stop 78. The stop 78 is secured to the panel 80, as illustrated in Fig. 2, and is disposed to be engaged by the lug 70 to limit the movement of the arm 32 in a clockwise direction, as illustrated in the drawing.

By adjusting the nut on the bolt 76, the force of the spring 64 may be varied, it being noted that when the lug 70 is seated against the stop 78 and the spring 64 is free from the nut on the bolt 76 that the spring 64 has a zero bias, and that when the spring 64 is seated against the nut on the bolt 76 by a movement of the arm 32 in a counter-clockwise direction about the cross-spring pivot that the spring 64 has a maximum bias. The spring 64 thus opposes the force of the cross-spring pivot over the major part of the travel of the movable arm to the circuit closing position.

A representation of the effect of the spring 64 is made in Fig. 4 in which curve 62 represents the combined force of the leaf springs 24 and the cross springs 34 and 36 as the movable arm pivots to actuate the springs 24 from an open circuit position to a circuit closing position. Curve 82 is representative of the force of the auxiliary leaf spring 64 over the same distance of travel, and curve 84 is representative of the combined forces of the springs 24, 34, 36, and 64. As illustrated, the resultant curve 84 is not as steep as curve 62 with the result that a greater degree of sensitivity in response to a change in the energization of coil or winding 48 is effected.

As illustrated in Fig. 1, the winding 48 of the electromagnet 40 is connected across the generator 10, one terminal of the winding 48 being connected by a conductor 86 through an adjustable resistor 88 and conductor 90 to one side of the armature winding 12, and the other terminal of the winding 48 being connected by conductor 92 through the primary winding 94 of a stabilizing transformer to conductor 16. The winding 94 of the stabilizing transformer is inductively coupled to a winding 96 that is connected across the shunt field winding 18 of the generator.

In operation with the regulator constructed as described, when the generator 10 is started and the voltage applied between conductors 14 and 16 is below the required value, then the energization of the winding 48 of the electromagnet is correspondingly decreased. The force of the main spring 52 being larger than the restraining magnetic pull on the armature 42 effects a movement of the arm 32 in a clockwise direction about the cross-spring pivot to actuate the leaf springs 24 away from the sloped stop 28 into circuit closing engagement to sequentially shunt additional sections of resistor 22 from the field circuit. By thus shunting sections of the resistor 22, the energization of the field winding 18 is increased with the result that the voltage across conductors 14 and 16 is increased.

Likewise if the voltage applied between conductors 14 and 16 is increased, the energization of the winding 48 is increased with the result that a stronger magnetic pull is applied to the armature 42 to actuate the arm 32 in a counter-clockwise direction to sequentially open the circuit between the leaf springs 24 and connect additional sections of the resistor 22 in the field circuit. This reduces the energization of the field 18 with the result that the voltage across conductors 14 and 16 decreases to the required value.

It is to be noted that with the contacts of the spring leaf members 24 in the open position that the cross-spring pivots 34 and 36 have a negative

bias, as represented by curve 58 of Fig. 3, tending to oppose the magnetic pull on the armature 42. It is also noted that, as shown by curve 82 of Fig. 4, the leaf spring member 64 has a positive bias tending to actuate the leaf spring members 24 to their circuit closing position. As the arm 32 moves in the clockwise direction as the magnetic pull is decreased, the bias of the cross-spring pivots 34 and 36 passes through a zero point and becomes an increasing positive force, while the bias of the leaf spring 64 becomes decreasingly small but opposes the increasing force of the pivot over the range of movement of the arm 32. By this arrangement, the forces of the springs cooperate, giving a resultant curve of changing force over the range of travel of the arm 32, as represented by curve 84 of Fig. 4, whereby the arm 32 is responsive to slight changes in the energization of the winding 48 of electromagnet 40 giving a substantially flat working range, as represented by the curve 98 of Fig. 5, the dotted curves 100 and 102 representing a range which may be obtained by adjusting the bolt 76. The curve 104 of Fig. 5 represents the type of sensitivity response of the circuit controlling device to a change from the energization of the winding 48 where the auxiliary leaf spring member 64 is not present.

By providing the spring member 64 as described hereinbefore, it is readily apparent that the unbalanced condition of the forces of the spring members which occurs when the cross springs 34 and 36 are made of heavier material are substantially compensated, and that the controlling device is quite sensitive to changes in voltage. Thus, a circuit controlling device is provided which, while being able to withstand high impact shocks, has an overall sensitivity comparable to the circuit controlling devices produced hereinbefore.

Although this invention has been described with reference to a particular embodiment thereof, it is, of course, not to be limited thereto except insofar as is necessitated by the scope of the appended claims.

I claim as my invention:

1. In a regulator for controlling an electric quantity over a predetermined working range, a control device comprising, a plurality of contact members disposed to be actuated in sequence, a member disposed to actuate the contact members, a cross-spring pivot for the actuating mem-

ber, a biasing means secured to the member to effect a non-linear pull thereon to actuate the member in one direction about its pivot, electro-responsive means disposed to be energized for actuating the member in the opposite direction about its pivot, a stop means disposed adjacent the actuating member to limit the movement thereof in the one or opposite directions, and a spring means carried by the actuating member, the spring means having a free end disposed for movement between the limits of the stop means whereby the spring means is free from bias when actuated the limit in the one direction and engages the stop means when actuated in the opposite direction to apply a compensating force to the actuating member to render the actuating member sensitive to a change in the energization of the electro-responsive means.

2. In a regulator for controlling an electric quantity over a predetermined working range, a control device comprising, a plurality of contact members disposed to be actuated in sequence, a member disposed to actuate the contact members, a cross-spring pivot for the actuating member, a biasing means secured to the member to effect a non-linear pull thereon to actuate the member in one direction about its pivot, electro-responsive means disposed to be energized for actuating the member in the opposite direction about its pivot, the cross-spring pivot being disposed to have a zero bias on the actuating member at some intermediate point between the limits of movement in said one and opposite directions, the cross-spring pivot thereby applying a biasing force to oppose movement of the actuating member as it approaches the limit of movement of said member in either of said one or the opposite directions, a stop means disposed adjacent the actuating member to limit the movement thereof in said one or opposite directions, and an elongated leaf spring carried by the actuating member, the leaf spring having a free end disposed for movement between the limits of the stop means whereby the leaf spring is free from bias when actuated the limit in the one direction and engages the stop means when actuated in the opposite direction to apply a force to the actuating member to oppose the movement of the actuating member in said opposite direction.

JOSEPH F. KOVALSKY.
